UNITED STATES PATENT OFFICE.

ALBERT H. DE VOE, OF ELIZABETH, NEW JERSEY, ASSIGNOR TO THE SINGER MANUFACTURING COMPANY, A CORPORATION OF NEW JERSEY.

RUFFLING AND STITCHING MACHINE.

1,074,845.

Specification of Letters Patent.

Patented Oct. 7, 1913.

Application filed May 23, 1910. Serial No. 562,798.

To all whom it may concern:

Be it known that I, ALBERT H. DE VOE, a citizen of the United States, residing at Elizabeth, in the county of Union and State of New Jersey, have invented certain new and useful Improvements in Ruffling and Stitching Machines, of which the following is a specification, reference being had therein to the accompanying drawings.

10 This invention has for its object to provide a ruffling, folding and stitching machine capable of convenient use in fulling and stitching endless folded seams extending completely around the garment, such as 15 the bottoms of ladies' skirts and other articles in which the operations upon the work end at substantially the point where they were begun.

According to the present improvement, 20 the ruffling mechanism includes a vibratory lever to which is attached by a universal joint connection a blade carrying lever adapted to be thrown laterally and upwardly out of operative position and provided with the usual ruffling blade normally disposed in alinement with the stitch-forming mechanism. The vibratory ruffling lever is provided with a shoulder by engagement with which the blade-carrying lever 25 can be maintained in retracted elevated position at one side of the line of seam when the machine is used for plain stitching in the final portion of the seam. The machine is provided with an upper fold-guide mounted 30 upon a carrying arm or lever having a universal joint connection with a normally stationary member of the machine which latter is provided with a stop-shoulder for holding it in retracted position above and at the 35 same side of the stitching line as the ruffling blade, when not in use; and it is further provided with a lower fold-guide slidingly mounted to be shifted out of operative position at the opposite side of the stitching line. By such construction and arrangement, as the folding, ruffling and stitching 40 approaches the starting point, the edge-folding members may be withdrawn from their respective folds of the superposed plies of 45 fabric and the ruffling blade laterally shifted out of operative relation with the work without disturbing the latter, so that the remainder of the seam may be guided and folded by hand while the stitching mech-

anism continues its action to finish the operation upon the garment. 55

The invention will be understood by reference to the accompanying drawings, in which—

Figure 1 is a front side elevation of a machine embodying the present improvements, and Fig. 2 an end view of the same with the face plate of the bracket-arm removed and the work-plate in transverse section to expose the parts beneath the same. Fig. 3 is a perspective view of the ruffling and folding devices and a portion of the stitch-forming mechanism. Fig. 4 is a perspective view of the upper fold-guide carrying lever and ruffling blade carrier with the universal 60 joint connections with their respective supports, showing the fold-guide and ruffling blade in retracted position. Fig. 5 is a rear side elevation representing the same universal joint connections in the positions 65 which they assume when their respective work-engaging members are in operative position. Figs. 6, 7, 8 and 9 are perspective views of the several members of the universal joint connection between the upper fold- 70 guide carrying lever and the presser-bar by which it is supported; and Figs. 10, 11, 12 and 13 are similar views of the universal joint connection between the ruffling blade carrying arm or lever and the vibratory 75 lever by which it is sustained. Fig. 14 is a perspective view showing a portion of the work produced by the machine. 80

In their general construction and arrangement of parts the stitch-forming and feeding and the ruffling mechanism of the present improvement, as represented in the drawings, are similar to those of my pending application Serial No. 552,948, filed 85 April 2, 1910. 90

The frame of the machine is constructed with the base 1 and bracket-arm formed with hollow standard 2 and overhanging portion 3 in the head 4 of which is journaled the vertically reciprocating needle-bar 5 with twin-needle clamp 6 carrying the diagonally arranged needles 7 coöperating with the loopers 8 beneath the work-plate 9 in the production of parallel double chain-stitch seams, the work being advanced to 100 space the stitches by the action of the feed-dog 10 carried by the feed-bar 11. The pressure member 12 of the presser-foot, op- 105

posed to the feed-dog 10, is pivotally attached to the shank 13 secured by means of the fastening screw 14 to the reduced lower end of the presser-bar 15 mounted in the 5 head 4 of the bracket-arm and having its upper end engaged by the pressure spring 16.

As described in detail in my said application, a longitudinally disposed rock-shaft 17 operatively connected with the main-shaft 10 of the machine is mounted in suitable bearings 18 upon the bracket-arm and carries in its forward portion a crank-arm 19 connected by means of a link 20 with an arm 21 fixed to the rearward end of a rock-shaft 22 15 journaled in the bracket-arm head 4 and having upon its forward end the depending arm 23 having a swivel connection 24 with the slotted vibratory ruffling lever 25 hung upon the stud-screw 26 of the lifting arm 27 20 which is fulcrumed at one end upon the pin 28 and has at its opposite end a pivotal connection 29 with the presser-bar 15. The rock-shaft 17 thus communicates through the several described connections operative 25 vibratory movements to the lever 25 in a plane in front of and parallel with the line of seam, while such lever follows the rising and falling movements of the presser-foot through its connection with the presser-bar. 30 The offset lower extremity 25^x of the lever 25 is formed with a transverse bearing boss 30 in which is journaled the rocking fulcrum-pin 31 formed upon its inner end with a bifurcated head 32 constituting a swivel-block 35 in the fork 33 of which is pivotally mounted by means of the transverse screw-pin 34 entering the aperture 35 thereof the flattened rearward end portion 36 of the ruffling blade carrying arm or lever 37 arranged at the opposite side of the needle-path from the ruffling lever 25. The opposite end portion of the lever 37 is bent downwardly and provided with a lateral ear 38 upon which is secured by means of the fastening screws 39 the shank of the ruffling blade 40 having its operative end portion provided with the usual needle-receiving notch 41 and fabric engaging serrations 42. Adjustably secured upon the bearing boss 30 45 of the lever 25 by means of the clamp-screw 43 is the split collar 44 provided with a laterally projecting stop-lug 45 whose end extends normally in substantial alinement with the pivotal pin 34 and registers with the rearwardly extending and slightly offset finger 36^x of the member 36 of the lever 37.

When the lever 37 is in normal or operative position, as represented in Fig. 5, the end of the stop-lug 45 is in contact with the 60 adjacent edge of the finger 36^x to prevent the lateral shifting of the lever 37 backwardly from the stitch line, while the inner extremity of the fork 33 of the swivel-block 32 engages the edge of the extension 36 to prevent the lateral displacement of the lever in

the opposite direction. When the retraction of the ruffling blade is desired, the presser-foot is first lifted and the lever 37 raised sufficiently to bring the top of the finger 36^x below the bottom of the lug 45, after which the lever 37 may be moved backwardly from the stitch-forming mechanism and retained in retracted elevated position, as represented in Fig. 4 and in dotted lines in Fig. 3, by engagement of the top of the finger 36^x with the bottom of the stop-lug 45, the return of the ruffling blade to operative relation with the stitch-forming mechanism being effected by reciprocal movements of the lever 37.

The reduced and shouldered forward end 80 portion 31^x of the rocking pin 31 has secured thereon by means of the set-screw 46 and clamp-nut 47 the hub 48 of a rigid arm 49 provided in the top of its extremity with a socket entered by the point of a threaded 85 thrust-rod 50 journaled at its upper end in the lug 51 formed upon the lever 25, between which and the guide-block 52 fitted upon the threaded portion of the rod 50 and forked to embrace the guide-rib 53 of the lever 25 is interposed the spring 54 by means of which the arm 49 is pressed downwardly, and, through its described connections therewith, the ruffling blade 40.

The presser-bar has adjustably secured 95 thereon above its lower reduced portion by means of the clamp-screw 55 the split collar 56 having a lateral arm 57 carrying the bearing boss 58 in which is journaled the rocking pin 59 having at its inner end a bifurcated head 60 constituting a swivel-block in the fork 61 of which is pivotally mounted, by means of the transverse screw-pin 62 entering the aperture 63 thereof, the member 64 to which is secured by means of the screw 65 the rearward extremity of the upper fold-guide carrying arm or lever 66. The forward end of the lever 66 has secured thereto one member of the inverted U-shaped shank 67 of the upper edge-folding guide 68 105 through which the undeturned marginal portion of the upper ply of fabric is delivered beneath the presser-foot and over the ruffling blade to the stitch-forming mechanism.

Adjustably secured upon the bearing boss 58 carried by the split collar 56 by means of the clamp-screw 69 is the split collar 70 provided with a laterally projecting stop-lug 71 whose end extends normally in 110 substantial alinement with the pivotal pin 62 and registers with the rearwardly extending and slightly offset finger 64^x of the folder-carrying lever member 64, while the lip 72 projecting from the lug 71 overhangs 115 the top of the finger 64^x so that its engagement with the same serves to limit the position of the folder 68 above the work-plate when the presser-bar is raised. The rocking fulcrum-pin 59 is held against endwise 120

130

movement within its bearing boss 58 by means of the swivel-block 60 at one end and the head of the screw 73 tapped into its opposite end.

5 When the parts are in the operative positions represented in full lines in Figs. 1, 2, 3 and 5, the shank 67 of the folder 68 straddles the lever 37, while the lever 66 is maintained in position by the engagement of the finger 64* with the outer end of the stop-lug 71 and the edge of the member 64 in advance of the aperture 63 engages the inner end of the fork 61 in the block 60. In order to disengage the folder 68 from the work, the lever 66 is first raised to bring the top of the finger 64* beneath the lower face of the lug 71, after which such lever is swung backwardly from the stitching mechanism to bring the finger 64* into engagement with the bottom of the lug 71 whereby such carrying lever is retained in its retracted position as shown in Fig. 4 and in dotted lines in Fig. 3.

The presser-bar 15 has secured thereon 25 by means of the set-screw 74 the usual collar 75 having the rearwardly extending lug 76 adapted to be engaged by the cam-shaped portion 77 of the lifting lever 78 pivotally mounted in the head 4 of the bracket-arm by 30 means of the fulcrum-pin 79, and the operation of the lever 78 causes the raising and lowering of the presser-bar 15, and with it the presser-foot, the ruffling lever 25, blade-carrying lever 37 and ruffling blade 40, and 35 the fold-guide carrying lever 66 and fold-guide 68. Fastened upon the throat-plate 80 by means of the rivets 81 is the corrugated wear-plate 82 having parallel grooves in its face to receive the points of the serrations 42 of the ruffling blade 40 in the normal action of the same while the ruffling is being performed.

Mounted within suitable bearings 83 and 45 84 beneath the work-plate at the front of the machine is the longitudinal slide-bar 85 having adjustably secured to its forward end by means of the set-screw 86 the depending boss 87 of a slide-block 88 whose upper portion is fitted within a slideway 89 formed 50 in the work-plate and having its upper surface flush with the top of the latter. Secured upon said block by means of screws 90 is the sliding base-plate 91 of the lower edge-folder 92 arranged within the stitching line 55 beneath the ruffling blade and having the auxiliary work-supporting plate 93 forming a continuation of the plate 91 at the opposite side of the stitching line. Secured upon the plate 91 by means of the screws 90 and by 60 the additional screw 90* is the foot 94 of a spring pressure blade 95 overlying the fold-guide 92 and projecting somewhat in advance of the same and serving to press downwardly upon the tongue 92* of the folder 92 65 and upon the wear-plate 82 the folded mar-

gin of the lower fabric so as to crease the same for preventing distortion or disarrangement as the latter is engaged by the serrated operative edge of the ruffling blade 40 in ruffling or crimping the same preparatory to attachment to the marginally folded upper ply by the stitch-forming mechanism.

Surrounding the slide-bar 85 and interposed between the rearward bearing 83 and the collar 96, adjustably secured thereon, is 70 a spring 97 tending to force the slide-bar forwardly to throw the lower fold-guide laterally of the stitching line into inoperative position; and upon the rearward end of the slide-bar 85 is adjustably secured by means of the set-screws 98 a collar 99 having the upwardly extending lug 100 upon which is pivotally mounted by means of the stud-screw 101 the rearward end of a latch-lever 102 formed in the lower edge of its free end 75 with a notch 103 adapted to engage the rearward end of the bearing 83 to lock the slide-bar in its rearward position but adapt it, when lifted by means of the finger-piece 104, to permit the slide-bar to move forwardly 80 under the action of its spring 97 so as to disengage the lower fold-guide from the lower ply of material overlying the plate 93.

In the use of the machine as thus described, the presser-foot is raised whereby the upper and lower fold-guides and ruffling blade are separated but are otherwise retained in operative relation with the stitching mechanism. The lower ply *a* of fabric is then introduced in the fold-guide 100 90 from the right and a fold *a'* thus formed therein, after which the upper ply of material *b* is introduced from the left into the fold-guide 60 and its margin turned downwardly into the fold *b'*, as represented in 105 Fig. 14. The presser-bar is then lowered, whereby the ruffling blade is forcibly brought into engagement with the lower ply of fabric. The machine being set in operation, parallel lines of stitching *c* and *d* are produced, the former passing through the body 110 of the upper ply of fabric and the folded margin of the lower ply near the edge, while the latter passes through the folded margin of the upper ply of fabric and the 115 body of the lower ply beyond the edge of its fold *a'*. While the stitching progresses, the ruffling blade 40 operates upon the folded marginal portion of the lower fabric and ruffles the same, as illustrated in Fig. 14. 120 To insure the proper creasing of the folded margin of the lower fabric so as to prevent disarrangement of the fold, the pressure blade 95 extends forwardly of the delivery end of the folder 92 and compresses the fold 125 upon the tongue 92* of the folder and the wear-plate 82.

In the ruffling and stitching of skirts and similar articles having endless seams, for which the present improvement is par- 130

ticularly designed, the body of the work is presented from the left and therefore covers the outer end of the work-plate, so that parts beneath the same are not conveniently accessible to the operator while the work is in place. For this reason, the shifting means for the lower of the independently acting edge-turning fold-guides, comprising the slide-bar 85 and the latch-lever 102, are disposed mainly at the opposite side of the ruffling-blade path from the supporting slide-block 88 constituting the fold-guide carrier. By this construction, means are provided upon the same side of the stitch-line as that to which the upper fold-guide is shifted whereby the lower fold-guide may be shifted out of operative relation with the stitch-forming mechanism. In closing a seam, therefore, both the upper and lower fold-guides may be laterally shifted out of operative relation with the stitch-forming mechanism without disturbing the work, so that the seam may be finished with the greatest convenience and with least possible loss of time.

It is evident that the details of construction of the present improvement are susceptible of considerable modification without departure from the scope of the invention.

Having thus set forth the nature of the invention, what I claim herein is:

1. In a sewing machine, the combination with stitch-forming mechanism, of ruffling mechanism comprising a vibratory lever, a carrier pivotally mounted upon and movable transversely of the direction of vibratory movement of said lever, a ruffling blade mounted upon said carrier, means disposed above the path of operative movement of the ruffling blade and detachably connected with the carrier for normally maintaining the ruffling blade in operative relation with the stitch-forming mechanism, independently-acting edge-turning fold-guides normally disposed respectively above and below said ruffling blade, a laterally swinging carrier for one of said fold-guides whereby the latter may be shifted to one side of the stitch-forming mechanism, and a laterally movable carrier for the other fold-guide adapted to be shifted in the opposite direction from the first-mentioned fold-guide carrier and provided with shifting means crossing the line of movement of the ruffling blade and controllable from the same side thereof as the first-mentioned fold-guide carrier.

2. In a sewing machine, the combination with stitch-forming mechanism, of ruffling mechanism comprising a vibratory lever, a carrier pivotally mounted upon and movable transversely of the direction of vibratory movement of said lever, and a ruffling blade mounted upon said carrier, a fold-guide

normally disposed in overlapping relation with said ruffling blade, a carrier-lever upon which said fold-guide is mounted, a normally stationary support, and a universal joint connection between said support and the carrier lever whereby the latter is adapted to be shifted laterally and upwardly out of operative position.

3. In a sewing machine, the combination with stitch-forming mechanism, of ruffling mechanism comprising a vibratory lever, a carrier having universal joint connection with said vibratory lever, and a ruffling blade mounted upon said carrier, a fold-guide normally disposed in overlapping relation with said ruffling blade, a carrier-lever upon which said fold-guide is mounted, a normally stationary support, a universal joint connection between said support and the carrier-lever whereby the latter is adapted to be shifted laterally and upwardly out of operative position, and stops mounted independently of the ruffling blade carrier and fold-guide carrying lever for maintaining them in retracted position.

4. In a sewing machine, the combination with stitch-forming mechanism, of ruffling mechanism comprising a vibratory lever, a blade-carrying lever, a ruffling blade mounted upon said blade-carrying lever, a swivel-block having a fulcrum-pin mounted upon and transversely of the direction of operative movement of said vibratory lever, a pivotal connection between said blade-carrying lever and said swivel-block disposed transversely of the latter's fulcrum-pin and positively acting means disposed wholly above the path of operative movement of the ruffling blade for restraining the latter from lateral displacement out of normal operative relation with the stitch-forming mechanism.

5. In a sewing machine, the combination with stitch-forming mechanism, of ruffling mechanism comprising a vibratory lever, a blade-carrying lever, a ruffling blade mounted upon said blade-carrying lever, a swivel-block having a fulcrum-pin mounted upon and transversely of the direction of operative movement of said vibratory lever, a pivotal connection between said blade-carrying lever and said swivel-block disposed transversely of the latter's fulcrum-pin, and a stop mounted independently of the blade-carrying lever and adapted to sustain the same when shifted laterally and upwardly out of operative position.

6. In a sewing machine, the combination with stitch-forming mechanism, of ruffling mechanism comprising a vibratory lever, a blade-carrying lever, a ruffling blade mounted upon said blade-carrying lever, a swivel-block having a fulcrum-pin mounted upon and transversely of the direction of operative movement of said vibratory lever, a pivotal connection between said blade-

carrying lever and said swivel block disposed transversely of the latter's fulcrum-pin, and a stop member carried by said vibratory lever and adapted to engage and sustain the blade-carrying lever in elevated position when the ruffling blade is shifted out of engagement with the work.

7. In a sewing machine, the combination with a stitch-forming mechanism, of ruffling mechanism comprising a vibratory lever, a blade-carrying lever, a ruffling blade mounted upon said blade-carrying lever, a swivel block having a fulcrum-pin mounted upon and transversely of the direction of operative movement of said vibratory lever, a pivotal connection transverse to said fulcrum-pin between said swivel-block and the blade-carrying lever intermediate the ends of the latter, and a stop member carried by 10 said vibratory lever normally out of sustaining relation therewith, but adapted to engage the end portion of the same opposite that carrying the ruffling blade when the latter is shifted laterally and upwardly out 15 of operative engagement with the work.

8. In a sewing machine, the combination with stitch-forming mechanism, of ruffling mechanism comprising a vibratory lever provided with a transverse bearing boss, 20 a blade-carrying lever, a ruffling blade mounted upon said blade-carrying lever, a swivel-block having a fulcrum-pin mounted in said bearing boss, a pivotal connection transverse to said fulcrum-pin between said 25 swivel-block and blade-carrying lever, and a collar adjustably mounted upon said bearing boss and provided with a stop-lug adapted to engage and sustain the blade-carrying lever when shifted laterally and upwardly 30 to disengage the ruffling blade from the work.

9. In a sewing machine, the combination with stitch-forming mechanism, of ruffling mechanism comprising a vibratory lever having a transverse bearing, a blade-carrying lever, a ruffling blade mounted upon said blade-carrying lever, a swivel-block having a fulcrum-pin mounted in the transverse bearing of said vibratory lever, a pivotal 40 connection transverse to said fulcrum-pin between said swivel-block and blade-carrying lever, an arm fixed upon said fulcrum-pin, a spring-pressed thrust-rod carried by said vibratory lever and engaging said fixed arm 45 for pressing the ruffling blade into operative engagement with the work, and adjusting means whereby the action of said thrust-rod upon the ruffling blade may be varied.

10. In a sewing machine, the combination 50 with stitch-forming mechanism, of ruffling mechanism comprising a vibratory lever having a transverse bearing boss, a blade-carrying lever, and a ruffling blade mounted upon said blade-carrying lever, a presser-foot, a 55 presser-bar to which the same is secured, a

fold-guide normally disposed in overlapping relation with said ruffling blade, a carrier-lever upon which said fold-guide is mounted, a bearing boss sustained by said presser-bar, and universal joint connections between the 60 blade-carrying lever and the bearing boss of said vibratory lever and between the fold-guide carrying lever and the bearing boss of said presser-bar, said connections each comprising a swivel-block having a fulcrum-pin mounted within its respective bearing boss, and a pivotal connection transverse to said fulcrum-pin with the carrying lever, whereby the latter is adapted to be shifted upwardly and laterally out of normal operative position.

11. In a sewing machine, the combination with stitch-forming mechanism, of ruffling mechanism comprising a vibratory lever having a transverse bearing boss, a blade-carrying lever, and a ruffling blade mounted upon said blade-carrying lever, a presser-foot, a presser-bar to which the same is secured, a fold-guide normally disposed in overlapping relation with said ruffling blade, 85 a carrier-lever upon which said fold-guide is mounted, a bearing boss sustained by said presser-bar, and universal joint connections between the blade-carrying lever and the bearing boss of said vibratory lever and between the fold-guide carrying lever and the bearing boss of said presser-bar, said connections each comprising a swivel-block having a fulcrum-pin mounted within its respective bearing boss, a pivotal connection transverse 90 to said fulcrum-pin with the carrying lever, whereby the latter is adapted to be shifted upwardly and laterally out of normal operative position, and a collar adapted to be secured upon said boss and provided with a stop-lug normally out of sustaining relation with said carrying lever, but adapted to engage the same when the latter is shifted laterally and upwardly out of operative 95 position.

12. In a sewing machine, the combination with stitch-forming mechanism, of ruffling mechanism comprising a vibratory lever, a carrier having a double pivotal connection therewith and movable upwardly and laterally in relation to said lever, and a ruffling blade mounted upon said carrier, an upper fold-guide normally disposed above said ruffling blade, a carrier-lever upon which said fold-guide is mounted, a normally stationary support, a double pivotal connection between said support and carrier-lever whereby the latter is adapted to be shifted upwardly and laterally relatively to the operative movements of said vibratory lever, 115 a lower fold-guide disposed below said ruffling blade, a sliding carrier therefor movable transversely of the direction of operative movement of said vibratory lever, 120 a spring for throwing the lower fold-guide 125

130

laterally out of operative position, and a latch-lever for locking the lower fold-guide in operative position.

13. In a sewing machine, the combination with stitch-forming mechanism, including a reciprocating needle, of ruffling mechanism comprising a vibratory lever, a blade-carrying lever, a ruffling blade mounted upon said blade-carrying lever, a swivel-block having a fulcrum-pin mounted upon and transversely of the direction of operative movement of said vibratory lever and rearward of the needle-path, a pivotal connection between said blade-carrying lever and said swivel-block disposed transversely of the latter's fulcrum-pin and also rearwardly of the needle-path, and means for locking said blade-carrying lever against movement upon its pivotal connection with the swivel-block.
14. In a sewing machine, the combination with stitch-forming mechanism including a reciprocating needle, of ruffling mechanism comprising a vibratory lever having a trans-

verse bearing, a blade-carrying lever disposed at one side of the path of reciprocation of the needle, a ruffling blade mounted upon said blade-carrying lever, a swivel-block having a fulcrum-pin mounted in the transverse bearing of said vibratory lever, a pivotal connection transverse to said fulcrum-pin between said swivel-block and blade-carrying lever, an arm fixed upon said fulcrum-pin at the opposite side of the needle-path from the blade-carrying lever, a spring acting upon said fixed arm for pressing the ruffling blade into operative engagement with the work, and means for adjusting the tension of said spring.

In testimony whereof, I have signed my name to this specification, in the presence of two subscribing witnesses.
